UNITED STATES PATENT OFFICE.

RALPH S. MUELLER, OF CLEVELAND, OHIO, ASSIGNOR TO BENJAMIN ELECTRIC MANUFACTURING COMPANY, A CORPORATION OF ILLINOIS.

SWIVEL PLUG.

1,411,293.

Specification of Letters Patent. Patented Apr. 4, 1922.

Application filed November 23, 1916. Serial No. 133,029.

To all whom it may concern:

Be it known that I, RALPH S. MUELLER, citizen of the United States, residing at Cleveland, in the county of Cuyahoga and 5 State of Ohio, have invented certain new and useful Improvements in Swivel Plugs, of which the following is a specification.

This invention relates to attachment plugs, and more particularly to swivel plugs. The 10 objects of the invention are to provide an improved plug which is of simple form and cheap to manufacture; which is easily attached to the conducting wires; which is convenient to operate in screwing it into the 15 lamp socket; which can be separated to expose the binding screws without removing screws or other parts; which relieves the cord strain; which amply protects the lead wires from liability of short circuit; and 20 finally a swivel plug comprising but two members which are readily connected or disconnected by relative rotation when desired and in assembled form have a swivelling motion relative to each other, but nevertheless 25 will not accidentally become disconnected. Further objects of the invention are in part obvious and in part will appear more in detail hereinafter.

The invention comprises the attachment 30 plug hereinafter described and claimed.

In the drawings, Fig. 1 represents a side elevation of one form of plug embodying the invention; Fig. 2 is a central longitudinal section on the line 2—2, Fig. 3; Fig. 4 is an 35 end view; Fig. 4 is a central longitudinal section on the line 4—4, Fig. 3, showing the two plug members partly connected, the cord being omitted; Fig. 5 is a side view of the insulated base or body; Fig. 6 is an end 40 view thereof; and Fig. 7 is a detail section, showing a modified form of cap and shell connection.

The plug shown in the drawings comprises essentially two members co-operatively associated, as will appear, one of which, marked 1, may be termed the base or body, and the other of which, marked 2, may be termed the cap or head. The two lead wires 3 of the conducting cord are connected to 45 the base or body while the cap turns relatively to the base or body in screwing the plug into a socket, avoiding the necessity of twisting or entangling the cord.

The base or body 1 is made of suitable

insulating material, such as rubber, fibre, 55 composition material, porcelain or the like. It is cylindrical in form with a single longitudinal passage 4 extending lengthwise along its axis through which the two lead wires are threaded. The single passage enables both wires to be pushed through at the same time, thereby saving time in assembling. At the advance end of the body, in other words the end first introduced into a 60 socket, the base or body is provided with a recess 5 communicating with the longitudinal passage 4, said recess in its bottom being provided with a threaded opening to receive the binding screw 6. This threaded opening is shown as a tapped opening in a 65 nut 7 embedded in the material of the body, but of course, might be formed in the body itself or in a part otherwise attached to the body. The binding screw 6 passes through a smooth opening in an end plate 8 which 70 has a portion marked 9 covering the longitudinal passage 4 and serving as an end contact, a bent intermediate portion 10 provided with an aperture 11 for the passage of the lead wire, and a depressed portion 12 seated 75 in the recess 5, as described, and serving as a base against which the lead wire is clamped by the head of the binding screw to produce good electrical connection between the lead wire and end contact, as will be readily understood.

The other lead wire of the conducting cord is bent outwardly and then back on itself so as to lie in a radial recess 12^a in the outer end of the base and in a longitudinal recess 80 13 in its outer surface. This double right angle turn of the wire serves to relieve any pull or strain on the cord and prevents pulling the wires away from the binding posts to which they are attached. In the inner 85 end of the base is a curved groove or channel 14 in which is located a conducting member 15 having two small tongues 16 diametrically opposite each other and extending radially outwardly a short distance beyond 90 the outer surface of the base. The conducting member 15 is preferably also slightly thicker than the channel in which it lies so that its surface is exposed beyond the end of the base, as shown in Fig. 5, although this 95 is not essential. Said member also has a longitudinal tongue 16^a which extends down 100 into the longitudinal recess 13, where it is

provided with a threaded aperture to receive a binding screw 17 for securing the end of the lead wire, thereby electrically connecting said wire to member 15.

5 The cap or head 2 comprises a suitably shaped member 18 made of non conducting material, such as rubber, fibre, porcelain, composition or the like, or which can even be turned from wood. It is provided with a 10 central aperture 19 for the wire and may be knurled or roughened anywhere on its exposed surface, as at 20, to give a better hand grip. This member 18, in prior swivel plugs, has usually been rigidly attached to the base 15 or body and has been held stationary when the swivelled part of the plug is turned to screw it into a socket. In my improved plug on the contrary, the head or cap turns relatively to the body and forms the support for 20 carrying the threaded conducting shell 21 which is screwed into the socket. Said shell is of the usual form and is suitably attached to the head. In Fig. 2 the shell is provided with a flange 22 through which holding 25 screws 23 are screwed into the head, while in Fig. 7 the head is of composition molded around tongues or a flange 24 on the shell, thus producing a firm and substantially integral connection of the parts. The shell 30 surrounds the body or base 1 and extends down toward but stops short of the end of said body in a manner to leave the end contact 9 exposed beyond the shell.

The swivelling movement between the base 35 and cap is produced by the engagement of the tongues 16 in an annular groove or channel 25 in the conducting shell 21 adjacent the member 18. This channel is pressed in the metal and its inner diameter is greater 40 than the small diameter of the shell across the roots of the threads therein. The tongues 16 project beyond the side surface of the base or body and the diameter across said tongues is also greater than the diameter 45 of the shell across the roots of its threads. Consequently when the tongues are fully seated in the groove or channel 25, as in dotted lines, Fig. 4, they turn in said channel but cannot escape therefrom accidentally. At the 50 same time the base or body is slightly smaller than the shell and can be turned or tilted to a position askew therein. By then rotating the base and cap the tongues 16 can be entered in turn into the threads of the shell, thereby 55 enabling the two parts of the plug to be separated by relative rotation and unscrewing movements, as shown in Fig. 4. The effect is due to the tongues forming an interrupted thread crossing the threads of the shell, as it 60 were, because of the askew position of the base in the body. Relative rotation of the two parts in the opposite direction enables the two parts to be assembled.

One distinct advantage of the plug de- 65 scribed is the absence of any distinction be-

tween the end cap or head and the ring usually attached to the threaded shell for turning it on the base. Both of these parts, in the present plug, are portions of the same piece and it is impossible to accidentally 70 twist the cord by turning the head instead of the ring. The plug can also be more readily inserted into sockets provided with lamp shades where the ring is difficult to reach and the head can be more readily grasped. The 75 plug comprises only two members which are readily connected or disconnected by a simple screwing or unscrewing operation without removing screws or other parts. It is also cheap to manufacture and can be sold 80 for a lower price in the market. Other advantages will readily occur to those skilled in the art.

What I claim is:—

1. A swivel plug, comprising two members one carrying an end contact and the other a threaded shell, said members being provided with means whereby they are attachable and detachable by relative rotation said threaded shell being non-rotatable 90 with respect to the member which carries it, said members when in assembled position being capable of relative rotation without movement of disconnection.

2. A swivel plug, comprising two members one carrying an end contact and the other a threaded shell, and means whereby said members may be attached and detached with respect to each other by relative rotation and longitudinal movement, said threaded shell being non-rotatable with respect to the member which carries it, said members when in assembled position being capable of relative rotation without movement of disconnection.

3. A swivel plug, comprising a base carrying an end contact, a head carrying a threaded shell, and means whereby said base and head may be attached and detached with respect to each other comprising non-yielding means on said base which traverse the threads of said shell for connecting or disconnecting the base and head, said base and threaded shell when in assembled position being capable of relative rotation without movement of disconnection.

4. A swivel plug, comprising a base carrying an end contact, a head carrying a threaded shell, having an annular recess, and means on said base adapted to traverse the threads of said shell for connecting or disconnecting the base and head, and in one position having turning movement in said annular recess to produce the swivelling movement.

5. A swivel plug, comprising a base having a contact at one end and a non-yielding radial projection at the other end, means for electrically connecting the lead wires thereto, and a threaded shell surrounding

said base and having an annular channel to receive said projection.

6. A swivel plug, comprising a base having a contact at one end and a non yielding 5 radial projection at the other end, means for electrically connecting the lead wires thereto, a threaded shell surrounding said base and having an annular channel to receive said projection, and a head supporting said 10 shell and rotatable therewith, said head having an opening therein the walls of which form a guide for the conductor leading to the plug contact.

7. A swivel plug, comprising a head carrying 15 a socket engaging threaded shell provided with an internal annular channel, and a base carrying an end contact and provided with an interrupted thread adapted to be passed through the threads of said 20 shell into said channel.

8. A swivel plug, comprising a head carrying a socket engaging threaded shell provided with an internal annular channel, and a base carrying an end contact and provided 25 with an interrupted thread adapted to be passed through the threads of said shell into said channel, said interrupted thread forming a part of the electrical connection of the lead wire to said threaded shell.

30 9. A swivel plug, comprising a base having a contact at one end and a radial projection at the other end, and a threaded shell surrounding said base and having an annular channel, said projection adapted to be 35 passed through the threads of said shell and forming part of the electrical connection of the lead wire thereto.

10. A swivel plug, comprising a base provided at one end with two diametrically opposite 40 projections, and a threaded shell surrounding said base, said projections being adapted to be threaded through the threads of said shell.

45 11. A swivel plug, comprising a base provided at one end with two diametrically opposite projections, and a threaded shell surrounding said base, said projections being adapted to be threaded through the threads of said shell, said base having an 50 end contact and an axial passage for leading the wire thereto.

12. A swivel plug, comprising a base provided at one end with two diametrically opposite projections, and a threaded shell surrounding 55 said base, said projections being adapted to be threaded through the threads of said shell, said base having an end contact and an axial passage for leading the wire thereto and to the shell contact.

60 13. A swivel attachment plug comprising a threaded shell contact for screwing into a threaded socket, a handle secured to said threaded shell contact, an insulating base located substantially inside said threaded 65 shell contact and having a swivel engagement

therewith, a center contact and binding terminal therefor supported by said insulating base, said threaded shell contact having an annular shoulder portion, and said insulating base being provided with a non-yielding 70 shoulder portion for cooperating with said annular shoulder portion, tending to hold said insulating base in said threaded shell contact, said insulating base being removable from said threaded shell contact at the inner 75 end thereof.

14. A swivel attachment plug comprising a threaded shell contact, a handle secured to said threaded shell contact, said threaded shell contact having an annular internal 80 shoulder, an insulating base having a cylindrical portion extending into said threaded shell contact and having a swivel engagement therewith, a wiring terminal supported by said insulating base, said insulating base 85 being provided with a non-yielding radially extending projection for engaging said annular shoulder, tending to hold said insulating base in position with the cylindrical portion within said threaded shell contact 90 member.

15. A swivel attachment plug comprising a threaded shell contact, a handle secured to said threaded shell contact, said threaded shell contact having an annular internal 95 shoulder, an insulating base having a cylindrical portion extending into said threaded shell contact and having a swivel engagement therewith, a wiring terminal supported by said insulating base, said insulating base 100 being provided with a non-yielding radially extending projection for engaging said annular shoulder tending to hold said insulating base in position with the cylindrical portion within said threaded shell contact 105 member, said insulating base being discon-nectable from said threaded shell contact by a movement including a tilting movement.

16. A swivel attachment plug comprising a threaded shell contact, a handle secured to 110 said threaded shell contact, said threaded shell contact having an annular internal shoulder, an insulating base having a cylindrical portion extending into said threaded shell contact and having a swivel engagement therewith, a wiring terminal supported by said insulating base, said insulating base being provided with a non-yielding radially extending projection for engaging said annular shoulder, tending to hold said insulating base in position with the cylindrical portion within said threaded shell contact 115 member, said annular shoulder being at the outer end of the threaded shell contact.

17. A swivel attachment plug comprising 120 a threaded shell contact, a handle secured to said threaded shell contact, said threaded shell contact having a shoulder, an insulating base having a cylindrical portion ex-125 tendsing into said threaded shell contact and 130

having a swivel engagement therewith, a wiring terminal for said threaded shell contact supported by said insulating base, said insulating base being provided with a non-yielding radially extending projection for engaging said shoulder tending to hold said insulating base with its cylindrical portion within said threaded shell contact, said projection being of metal and forming part of the electrical circuit between said threaded shell contact and its wiring terminal.

18. A swivel attachment plug comprising a threaded shell contact, a handle secured to said threaded shell contact, said threaded shell contact having an internal annular shoulder, an insulating base having a cylindrical portion extending into said threaded shell contact, a binding plate mounted on said insulating base, said binding plate having a portion integral therewith forming a non-yielding radially extending projection for engaging said annular shoulder tending to hold said insulating base with the cylindrical portion within said threaded shell contact.

19. A swivel shell attachment plug comprising a threaded shell contact, having an internal annular shoulder, an insulating base

located substantially within said threaded shell contact, said threaded shell contact being swiveled with respect to said insulating base, said insulating base being provided with a non-yielding shoulder for engaging said annular shoulder portion tending to hold said insulating base in place in said threaded shell contact, said insulating base being insertable through the inner end of the threaded shell contact, and a wiring terminal supported by said insulating base.

20. A swivel shell attachment plug comprising a threaded shell contact, having an internal annular shoulder, an insulating base located substantially within said threaded shell contact, said threaded shell contact being swiveled with respect to said insulating base, said insulating base being provided with a non-yielding shoulder for engaging said annular shoulder portion tending to hold said insulating base in place in said threaded shell contact, said insulating base being insertable through the inner end of the threaded shell contact, and a center contact supported by said insulating base.

In testimony whereof I affix my signature. 55
RALPH S. MUELLER.
